Register Company, Dayton, Ohio, a corpora-
tion of Maryland

Original application September 25, 1941, Serial
No. 412,346. Divided and this application
August 24, 1942, Serial No. 455,840

5 Claims. (Cl. 235—6)

This invention relates to a tens carrying mechanism and is a division of our application Serial No. 412,346, filed September 25, 1941.

The present invention is embodied in a machine of the general type disclosed in Letters Patent of the United States Nos. 1,619,796; 1,761,542; and 1,916,535, issued, respectively, March 1, 1927; June 3, 1930; and July 4, 1933, to Bernis M. Shipley; No. 2,141,332, issued December 27, 1938, to Charles H. Arnold; and No. 2,176,561, issued October 17, 1939, to Everett H. Placke.

The present invention is directed to a tens transfer mechanism adapted to a machine which includes four totalizer lines, each line consisting of a maximum of ten sets of interspersed totalizer wheels.

The principal object of the invention is to provide a novel tens transfer mechanism which is particularly adapted to a machine including interspersed totalizers.

Another object of the invention is the provision of improved transfer mechanism for transferring tens digits from lower denominations to higher denominations.

Another object of the invention is to provide novel means to shift the totalizers laterally, for the purpose of transferring from lower to higher denominational orders, without disturbing the previous selection of any totalizers under control of a selecting differential mechanism.

A specific object of the invention is to provide a tens transfer mechanism wherein the tens transfer elements are adjacent the amount entering actuators for interspersed totalizers; means for laterally shifting the row of interspersed totalizers for selecting a totalizer for actuation; and other means to shift the selected totalizer line laterally into alignment with the tens transfer segments after the amount has been entered, preparatory to receiving the tens transfer entries.

With these and incidental objects in view, the invention includes certain novel features of construction and combinations of parts, the essential elements of which are set forth in appended claims and a preferred form or embodiment of which is hereinafter described with reference to the drawings which accompany and form a part of this specification.

In said drawings:

Fig. 1 is a cross-sectional view taken just to the right of one of the amount banks and showing the differential mechanism associated with

said amount bank, and the four totalizer lines actuated by said differential mechanism.

Fig. 2 is a detail view of the tens transfer mechanism for the amount bank shown in Fig. 1.

Fig. 3 is a cross-sectional view of the machine, taken immediately to the right of one of the transaction banks, showing in particular the differential mechanism associated with said transaction bank, and the mechanism controlled by said differential mechanism for shifting the corresponding totalizer line laterally to select the different sets of totalizer wheels for engagement with the amount actuators.

Fig. 4 is a diagrammatic front elevation of a portion of the machine, showing in particular the mechanism for shifting one totalizer line laterally to select the different sets of totalizer wheels thereon for engagement with the amount actuators.

Fig. 5 is a right side elevation of the totalizer engaging mechanism and illustrates one totalizer connected thereto.

Fig. 6 is a right side elevation of the totalizer line shifting cams for shifting the four totalizer lines a slight distance laterally to align the selected set of totalizer wheels with the tens transfer mechanism.

GENERAL DESCRIPTION

30 The keyboard of the machine embodying the instant invention comprises a plurality of rows of amount keys which in adding operations control the positioning of corresponding amount differential mechanisms, said differential mechanisms in turn being arranged to transmit the values of the depressed amount keys to the printing mechanism and to the wheels of the selected totalizer. In sub-total or total recording operations, the amount differential mechanisms, 35 which include an amount actuator for each denominational order, are positioned by the wheels of the selected totalizer in accordance with the amount standing on said totalizer wheels, said differential mechanisms in turn transmitting such positioning to the printing mechanism in the usual manner.

Instead of the conventional three lines of totalizers, the present machine is provided with four lines of totalizers, each supporting a maximum of ten sets of interspersed totalizer wheels, which wheels are engageable with the amount actuators of the differential mechanisms for actuation thereby. The four lines of interspersed totalizers are located around the amount actuators, as is the usual custom, and each of said

totalizer lines is mounted in a framework which is shiftable laterally to aline the different sets of totalizer wheels with the amount actuators, and is also shiftable radially to engage and disengage the selected set of wheels with and from said actuators.

Four rows of transaction keys, corresponding to the four totalizer lines, are provided for controlling the lateral shifting of the corresponding totalizer frameworks to aline the various sets of totalizer wheels with the amount actuators. The four rows of transaction keys likewise control the positioning of four corresponding add selecting disks, which, in cooperation with their respective feeler mechanisms, control the radial shifting movement of the framework for the corresponding totalizer lines to cause the selected set of totalizer wheels on the selected totalizer line to be engaged with and disengaged from the amount actuators.

The amount differential mechanisms are driven by a main cam shaft, which in adding operations makes one revolution and in sub-total recording or reading operations and in total recording or resetting operations makes two such revolutions. Adding operations, which require one revolution of the main cam shaft, are commonly referred to as one-cycle operations, and sub-total and total recording operations, which require two revolutions of the cam shaft, are commonly referred to as two-cycle operations.

In adding operations, initial movement of the differential mechanisms, under influence of the cam shaft, causes said mechanisms to be positioned under control of the depressed amount keys, and, during this positioning, the framework of the selected totalizer line is shifted laterally, under influence of the depressed transaction keys, to aline the selected set of totalizer wheels thereon with the amount actuators. After the selected set of totalizer wheels has been alined with the amount actuators, the corresponding feeler mechanism, in cooperation with the corresponding selecting disk, which has previously been positioned under influence of the depressed transaction key, causes the totalizer engaging mechanism to be connected to the shiftable framework for the selected totalizer line. Operation of the totalizer engaging mechanism causes the selected set of totalizer wheels to be engaged with the amount actuators after said actuators have been positioned by the amount keys, as explained above, and return movement of said actuators, under influence of the main cam shaft, rotates the selected totalizer wheels in accordance with the values of said depressed amount keys to add in said wheels the amount set up on the keyboard.

A novel tens transfer mechanism, which functions in adding operations, is provided for transferring tens digits from lower to higher denominations. In adding operations, when the wheels of the selected totalizer pass from 9 to 0 while being rotated in an additive direction by the amount actuators, a long tooth on said wheels trips the transfer mechanism for the next higher order. After the amount actuators have completed their return movement, the framework for the selected totalizer line receives an auxiliary lateral shifting movement to move the selected set of totalizer wheels out of alinement with the amount actuators and into alinement with a series of transfer segments which are located adjacent to the corresponding amount actuators, there being one such transfer segment in each denominational order of each of the four totalizer lines except the

lowest order. After the selected totalizer wheels are engaged with the transfer segments, said segments are released to the driving action of their springs, to cause the tripped segments to advance the wheels of the next higher order one digit, to effect a tens transfer.

The selected set of totalizer wheels remains in alinement with the transfer segments at the end of the machine operation and are shifted back into alinement with the amount actuators at the beginning of the succeeding operation, at which time all the previously tripped transfer segments are restored to untripped position.

DETAILED DESCRIPTION

Amount Differentials

The amount keys 54 (Fig. 1) control the positioning of corresponding amount differential or actuator mechanisms, and, inasmuch as this differential mechanism is substantially duplicated in each denominational order, it is believed that a description of the mechanism of one such denominational order, as shown in Fig. 1, will be sufficient for the purpose of this specification.

The amount keys 54 (Fig. 1) of the denominational row here shown, which is representative of all the rows of amount keys, are mounted in a framework 100 supported by rods 101 and 110 in turn supported by the main framework of the machine. Depresssion of any one of the amount keys 54 rocks a zero stop pawl 102 counter-clockwise out of the path of a projection 103 of an amount actuator 104 free on a shaft 105 journaled in the main frames 50, and moves the lower end of said depressed key into the path of said projection 103. When no amount key 54 is depressed, the zero stop pawl 102, under influence of a spring 109, is retained in the path of the projection 103 and breaks the latch for this amount bank in zero position, as will be explained later.

The actuator 104 (Fig. 1) has therein an angular camming slot 111, through which extends a stud 112 in a latch 113 pivoted on a stud 114 carried by a latch arm 115 free on the shaft 105. The stud 112 also extends through an angular camming slot 116, which is a companion slot to the slot 111, said slot 116 being in a differential balance plate 117 free on the shaft 105. A foot-shaped extension of the latch 113 has thereon a shoulder 118, which, in cooperation with a similar shoulder on a latch driving segment 119 free on the shaft 105, forms a driving connection between said segment and the latch arm 115. A link 120 operatively connects the driving segment 119 to an operating lever 121 pivoted on a stud 122 in a partition plate 123 for this particular amount bank, there being such a partition plate for each amount bank.

A boring in a downward extension of the lever 121 freely engages a rod 124, opposite ends of which are secured in similar arms 125 (only the left-hand arm being shown here), said arms being pivoted on studs (not shown) similar to and in axial alinement with the stud 122, said studs being secured in their corresponding partition plates 123. Each of the arms 125 carries a set of rollers 126 and 127, which cooperate, respectively, with their corresponding set of companion plate cams 128 and 129 (only one set here shown), secured on a main cam shaft 130 journaled in the main framework of the machine.

A clutch mechanism, not shown here but well known in the art, operatively connects the main

cam shaft 130 to the operating motor, said motor being arranged to drive the shaft 130 one clockwise revolution in adding operations and two such revolutions in reading and resetting operations. Revolution of the main cam shaft 130, by means of the cams 128 and 129, imparts an invariable oscillating movement to the arms 125, the lever 121, and the latch-operating segment 119, first clockwise and then counter-clockwise.

Initial movement clockwise of the segment 119, by means of the shoulder thereon in cooperation with the shoulder 118 on the latch 113, carries said latch and the latch arm 115 clockwise in unison therewith. The latch 113, by means of the stud 112 in cooperation with the slots 111 and 116, carries the actuator 104 and the balance plate 117 clockwise in unison therewith. In this case, a spring 167 and the downward inertia of the balance plate 117 causes the slot 116, in cooperation with the stud 112, to retain the latch in engagement with the segment 119 and thereby overcomes any tendency of the slot 111 in the actuator 104 to cam said latch 113 out of engagement with the shoulder on the operating segment 119. The actuator 104 moves in unison with the segment 119 until the projection 103 engages the lower end of the stem of the depressed key 54, which obstructs further clockwise movement of said actuator 104. Stopping of the actuator 104 causes the cam slot 111, in cooperation with the stud 112, to cam the latch 113 counter-clockwise to disengage the shoulder 118 from the segment 119 and simultaneously to engage an arcuate surface on the top of said latch with the corresponding one of a series of alining notches 132 in a curved alining bar 133 secured to the partition plate 123 for this particular amount bank, said plate 123 being supported by the shaft 105 and the rods 134, 135, and 136, in turn supported by the main framework of the machine. As the segment 119 continues its clockwise movement without interruption, an arcuate surface thereon passes in the path of the foot-shaped extension of the latch 113 to lock said latch, the arm 115, and the actuator 104 in set positions.

The actuator 104 has, on the periphery thereof, a plurality of gear teeth 137 arranged to cooperate with the different sets of totalizer wheels 138 to 141 inclusive, carried respectively by the Nos. 1, 2, 3, and 4 totalizer lines.

In adding operations, after the actuator 104 has been positioned, as explained above, the selected totalizer line is shifted radially to engage the corresponding one of the selected set of totalizer wheels thereon with the teeth 137 of the actuator 104. After the corresponding one of the selected set of totalizer wheels has been engaged with the actuator 104, return movement counter-clockwise of the operating segment 119 moves the arcuate surface on said segment beyond the foot-shaped extension of the latch 113 and simultaneously causes a stud 142 carried thereby to engage a raised surface on the latch arm 115 to return said arm and, through the stud 112 and the slots 111 and 116, the actuator 104 and the balance plate 117 counter-clockwise in unison therewith. Counter-clockwise movement of the latch arm 115 causes the alining notch 132, in cooperation with the arcuate surface on the latch 113 and the spring 167, to reengage the shoulder 118 on said latch 113 with the corresponding shoulder on the operating segment 119. During its return movement counter-clockwise, the actuator 104 rotates the wheel 138 of the selected totalizer in

an additive direction, in accordance with the value of the depressed amount key 54, to add said value into said wheel.

An aliner 143 (Fig. 2), in cooperation with the teeth 137, retains the actuator 104 in set position in all types of operations. Obviously the aliner 143 is disengaged while the actuator 104 is being positioned.

The differential movement of the actuator 104 is transmitted to the indicator mechanism by the well-known minimum movement mechanism including beam 145, link 147, and segment 148. The link 147 also transmits the differential setting movement of the actuator to type carriers 158, through segment 150, link 152, segment 153, and the well-known internal-external gear mechanism 155, the latter being fully disclosed in United States Patent No. 1,693,279, issued November 27, 1928, to Walter J. Kreider.

Transfer mechanism

A tens transfer mechanism is provided for transferring tens digits from lower to higher denominations. The transfer mechanism for each totalizer line comprises a transfer segment and its associated tripping mechanism for each denominational order, except the lowest order, and, when a totalizer wheel passes from 9 to 0 while traveling in an additive direction, the long tooth thereon trips the transfer mechanism for the next higher order. The transfer segments are located adjacent to and parallel with the corresponding amount actuators; therefore, after the amount actuators have completed their return movements, to enter the value of the amount set up on the amount keys in the selected totalizer wheels, it is necessary to shift the selected totalizer line or lines a slight distance laterally to aline said wheels with the corresponding transfer segments. Immediately thereafter, the previously tripped transfer segments function to add one in the totalizer wheels of the next higher orders.

During the auxiliary shifting of the totalizer line to move the selected totalizer wheels into alinement with the transfer segments, said line is partially disengaged to insure that said wheels do not stumble on the transfer segments and to insure that adjacent wheels do not stumble on the teeth of the actuators. The selected totalizer wheels remain in engagement with the transfer segments at the end of machine operation and are disengaged therefrom immediately at the beginning of the succeeding operation, after which the totalizer line is restored laterally to aline the wheels thereof with the amount actuators.

Inasmuch as the transfer mechanisms for the different denominational orders and for the different lines of totalizers are identical, it is believed that a description of the transfer mechanism for the denominational order of the No. 1 totalizer line shown in Fig. 1, will suffice.

The transfer mechanism for the denominational order of the No. 1 totalizer line, shown in Fig. 1, comprises a transfer segment 170 (Fig. 2) pivoted on a stud 171 in a plate 172 supported by the rods 134, 135, and 136. A spring 173 urges the segment 170 counter-clockwise to normally maintain a camming surface 174 thereon in engagement with a stud 175 in a transfer operating arm 176 free on a stud 177 in the plate 172. A spring 178 urges the arm 176 clockwise to normally maintain a bent-over ear 179 thereon in contact with a retaining tooth 180 on a trans-

fer trip yoke 181 free on a stud 182 in the plate 172 for the order here shown.

When the selected No. 1 totalizer wheel 138, in the next lower order to the order shown in Figs. 1 and 2, passes through zero, a long tooth 183 thereon engages a bent-over extension 184 on the yoke 181 and rocks said yoke counter-clockwise to disengage the tooth 180 from the ear 179 to release the arm 176 to the action of the spring 178, which rocks said arm a slight distance clockwise until the ear 179 passes beyond the tooth 180 and until a depending finger 185 of said arm 176 contacts a stud 186, which at this time is in the position here shown in dot-and-dash lines. The stud 186 is secured in a restoring disk 187 fast on the shaft 105, there being such a disk for each denominational order, with the exception of the lowest order. Also fast on the shaft 105 (Fig. 2) is a crank 188 carrying a stud 189 embraced by a slot in a cam lever 190 free on a stationary stud 191. Angularly disposed arms of the lever 190 carry, respectively, rollers 192 and 193, which cooperate respectively with the peripheries of companion plate cams 194 and 195 secured on the main cam shaft 130.

The timing of the cams 194 and 195 is such that initial movement of said cams, through the lever 190, rocks the disk 187 clockwise, causing the stud 186, in cooperation with the depending finger 185, to restore the operating arm 176 counter-clockwise against the action of its spring 178 until the ear 179 passes beyond the tooth 180. Continued rotation of the cams 194 and 195 returns the disk 187 and the stud 186 a slight distance counter-clockwise to permit the ear 179 to engage the tooth 180 to latch the transfer mechanism in untripped position, and to position the stud 186 a slight distance away from the finger 185, as shown in dot-and-dash lines in Fig. 2. Restoring movement counter-clockwise of the operating arm 176 causes the stud 175, in cooperation with the camming surface 174, to restore the tripping segment 170 clockwise against the action of the spring 173.

It should be noted that the restoring of the transfer mechanism takes place during initial movement of the amount actuators 104 and prior to the time the selected totalizer wheels are engaged therewith. Return movement of the amount actuator for the next lower order wheel 138 (Fig. 2) rotates said wheel in an additive or clockwise direction, causing the long tooth 183 thereon to engage the extension 184 to trip the yoke 181, in the manner explained above. After the amount actuator has completed its return movement, the transfer shift is imparted to the No. 1 totalizer line to move the wheels 138 of the selected totalizer into alignment with the transfer segments 170, and immediately thereafter the cams 194 and 195 return the disk 187 counter-clockwise to the position shown here. The operating arm 176 moves clockwise in unison with the disk 187, causing the stud 175, in cooperation with the camming surface 174, to permit the spring 173 to rock the segment counter-clockwise to advance the totalizer wheel 138, for the order here shown, one digit to effect a tens transfer.

The mechanism for imparting auxiliary or transfer shifting movement to the totalizer line will be explained later herein in connection with the totalizer selecting and engaging mechanism.

In reading and resetting operations, the wheel 138 (Fig. 2) is reversely rotated by the amount actuator 104 until the long tooth 183 thereon

comes into contact with the extension 184 to locate said wheel in zero position and to position the actuator and the recording mechanism in accordance therewith.

5   *Transaction keys and differential mechanism therefor*

The differential mechanism for each of the four rows of transaction keys is similar in every respect to the amount differential mechanism shown in Fig. 1 and explained above, and, as the transaction differential mechanism is substantially duplicated for each row of transaction keys, it is believed that a description of the differential mechanism for the first row of transaction keys, shown in Fig. 3, will suffice for all.

The transaction keys 55 for the first transaction bank are mounted in a key frame 198 supported by the rods 101 and 110 in exactly the same manner as the amount key banks. Depression of any one of the transaction keys 55 rocks a zero stop pawl 199 counter-clockwise out of the path of a projection 200 of an actuator 201 free on the shaft 105, said actuator 201 being operatively connected to a balance plate 202 by means of angular slots in said actuator and said plate, in cooperation with a stud in a latch 203 pivotally mounted on a latch arm 204 free on the shaft 105. The latch 203 cooperates with a shoulder on a differential operating segment 205 free on the shaft 105 and connected by a link 206 to an operating lever 207 free on a stationary stud 208. The cam lever 207 carries rollers 209 and 210, which cooperate, respectively, with the peripheries of companion plate cams 211 and 212 secured on the main cam shaft 130. The cams 211 and 212 function to rock the actuator 201 first clockwise and back to normal position during each revolution of said main shaft 130.

30   The parts of the transaction differential described briefly above are similar to and function exactly like similar parts of the amount actuator shown in Fig. 1 and described earlier herein.

35   Initial movement clockwise of the lever 207, through the segment 205 and the latch 203, carries the actuator 201 clockwise in unison therewith until the projection 200 contacts the stem of the depressed transaction key, which positions said actuator according to the value of said depressed transaction key. This disengages the latch 203 from the segment 205 in exactly the same manner as described for the amount bank, thus permitting said segment and the lever 207 to complete their initial movements clockwise independently thereof. When the lever 207 nears the terminus of its initial movement clockwise, a roller 213 carried thereby engages an arcuate surface on a beam 214 pivoted on the arm 204, to position said beam in accordance with the depressed transaction key. The rearward end of the beam 214 is bifurcated to embrace a stud 215 in a link 216, the upper end of which link is pivotally connected to a gear sector 217 secured to one of a plurality of nested tubes 218 free on the shaft 149. The lower end of the link 216 is pivotally connected to a segment 219 free on the shaft 151, and connected by a sleeve 220 to a crank 221 (Figs. 3 and 4) is connected by a link 222 to a segment 223 free on the shaft 105, said segment meshing with a gear 224 secured on a short shaft 225 journaled in plates 226 and 227 supported by the rods 134, 135, and 136 (Fig. 1).

40   Also secured on the shaft 225 (Figs. 3 and 4) 45   is a disk carrying three studs 229 (only two

being shown), which freely engage corresponding borings in the left-hand face of a drum cam 230 free on the shaft 225. The cam 230 has a helical cam groove 231, which cooperates with a roller 232 secured in a slide 233 shiftably mounted on the top surface of a yoke 234 by means of studs in said slide in cooperation with horizontal slots in said yoke, said roller 232 arranged to extend through one of said horizontal slots. The yoke 234 is free on the shaft 225, but is held against rotary movement by a roller 235 carried thereby, in cooperation with a horizontal slot in a bracket 236 secured to the plate 226, and by means of a vertical slot in the left-hand extension thereof, in cooperation with a stud 237 in the plate 227. An annular groove 238 (Fig. 4) in a reduced portion of the drum cam 230, in cooperation with a slotted bracket 239 secured to the yoke 234, maintains said drum cam and said yoke in fixed lateral relationship to each other.

An upturned portion of the slide 233 (Figs. 3 and 4) has therein a slot 240, which engages an annular groove 241 in a hub portion of a totalizer frame side member 242, said hub portion having therein a boring which freely engages a shaft 243 which is arranged to be shifted radially in a manner presently to be described, to engage the selected set of totalizer wheels with the amount actuators. The side member 242 supports the right-hand end of the No. 1 totalizer line or rod, while a similar side member 258 (Fig. 1), also slidably mounted on the shaft 243, supports the left-hand end of said No. 1 totalizer line, said side members, together with the No. 1 totalizer line and the shaft 243, forming a shiftable framework for engaging and disengaging the No. 1 totalizer wheels with and from the amount actuators. The lower ends of the side members 242 and 258 have therein similar slots which engage similar tooth-shaped blocks 244 (Fig. 4) carried by the plates 123, said blocks being the shape of and in alignment with the teeth in the actuators 104 (Fig. 1).

The roller 235 (Figs. 4 and 6) extends into a cam slot 244 in one of four camming extensions on a transfer shift cam 245 free on the shaft 105. An extension 246 of the cam 245 has pivotally connected thereto the upper end of a link 247 having a stud 249 in the lower end, which normally engages a slot in an arm 248 fixedly connected, by a hub free on a stud 250 in the plate 226, to a cam arm 251. The cam arm 251 carries rollers 252 and 253, which cooperate respectively with the peripheries of companion plate cams 254 and 255 secured on the main cam shaft 130.

The timing of the cams 254 and 255 is such that the arms 251 and 248 and the cam 245 (Figs. 5 and 6) are shifted clockwise prior to initial movement of the amount actuators 104. Clockwise movement of the cam 245, by means of the slot 244 in cooperation with the roller 235, shifts the yoke 234 toward the left, as viewed in Fig. 4, which movement is transmitted by the bracket 239 to the drum cam 230 and thence by the cam groove 231 and the roller 232 to the slide 233. This shifts the member 242 and the No. 1 totalizer framework a slight distance toward the left to move the selected totalizer wheels out of alignment with the transfer segments 170 and into alignment with the amount actuators 104 (see also Figs. 1 and 2).

After the selected set of wheels on the No. 1 totalizer has been shifted out of alignment with

the transfer segments, as explained above, the roller 213 (Fig. 3) engages the beam 214 to position said beam in accordance with the depressed transaction key, and this positioning is transmitted by the link 216 to the sector 217, the segment 219, and the crank 221. The crank 221, by means of the link 222, rocks the gear segment 223 from zero position, as here shown, in a clockwise direction to a position corresponding to the depressed transaction key. Clockwise movement of the segment 223 (Fig. 3) rotates the gear 224, the shaft 225, and the drum cam 230 counterclockwise, causing the cam groove 231 (Fig. 4) in said drum cam, in cooperation with the roller 232, to shift the slide 233 and the totalizer framework, comprising the members 242 and 258 and the No. 1 totalizer line, toward the left, as here viewed, to align the set of totalizer wheels 138 corresponding to the depressed transaction key 55 with the amount actuators 104.

In adding operations, after the selected set of totalizer wheels has thus been aligned with the amount actuators, radial shifting movement is imparted to the shaft 243 (Figs. 1 and 3), as will be presently explained, to engage the selected totalizer wheels with the amount actuators 104, after said actuators have been positioned under influence of the depressed amount keys. Return movement counter-clockwise of said actuators rotates said wheels in an additive direction to enter the amount therein, and, after said actuators have completed their return movements, the totalizer wheels are slightly disengaged from the actuators, and the cams 254 and 255 (Fig. 6) function to shift the No. 1 totalizer a slight distance to the right to move the selected set of wheels thereon into alignment with the transfer segments 170. After this, the No. 1 totalizer line is returned to full engaged position and the tripped transfer segments 170 (Fig. 2) then function, under influence of their cams 194 and 195, to effect the transfer of tens digits from lower to higher denominations, in the manner explained earlier herein.

At the end of a machine operation, the selected set of totalizer wheels remains in alignment with the transfer segments 170 and is returned into alignment with the amount actuators 104 at the beginning of the succeeding operation.

Totalizer engaging mechanism

In machines of the type to which the present invention is shown applied, a selecting means under control of the transaction banks of keys is provided for selecting the line of totalizers to be engaged with the amount differentials 104 for receiving entries. Since this selecting means forms no part of the present invention, it is not disclosed herein. For a complete disclosure thereof, reference may be had to the parent case, referred to hereinbefore. For the purpose of understanding the present invention, it is only necessary to know that, when a totalizer on a selected totalizer line is to be engaged with the amount actuators, a stud 310 (Fig. 5) is rocked into engagement with a notch 348, at the proper time, and when said notch is aligned with the stud 310.

The stud 310 is carried on a link 311 pivotally connected to the end of a lever 312 free on a stud 313 in the frame 51. A link 314 pivotally connects the lever 312 to the end of a lever 315 secured on the shaft 243, said lever carrying a roller 316, which engages a camming slot 317 in a totalizer engaging plate 318 secured to the frame

51. A tenon on the end of the shaft 243 rotatably supports a roller 319, which engages a radial slot 320 in the plate 318. The left-hand end of the shaft 243 supports a roller, similar to the roller 319, which cooperates with a radial slot in a left-hand engaging plate similar to the plate 318, said plate having a camming slot, similar to the slot 317, which cooperates with a roller carried by a crank secured on the left-hand end of the shaft 243, such engaging mechanism for the left-hand end of the shaft 243 not being shown here.

52. A spring 321 (Fig. 5) urges the link 311 clockwise to normally maintain a stud 322, carried thereby, in engagement with a downward branch of an L-shaped slot 323 in the frame 51. The stud 322 is normally locked in the downward branch of the slot 323 by an arcuate surface 324 on one leg of a totalizer engaging spider 326 integral with a hub 321 free on the shaft 105. The hub 327 (Fig. 5) has therein a clutch cut, which engages corresponding tenons on a similar hub also free on the shaft 105 and having integral therewith a crank 329. The crank 329 pivotally supports the upper end of an engaging link 330 having in the lower end thereof a stud 331, which cooperates with a slot in an arm 332 secured to a hub 333 free on a stationary stud 334. Also secured to the hub 333 is a cam lever 335 carrying rollers 336 and 337, which cooperate respectively with companion plate cams 338 and 339 secured to the main shaft 130. The cams 338 and 339 drive the spider 326 in adding operations, and the stud 331 is maintained in engagement with the slot in the arm 332 in such operations by means not shown herein.

53. In adding operations, the cams 338 and 339 rock the spider 326, the first movement of said spider being in a counter-clockwise direction. Counter-clockwise movement of the spider 326, at the beginning of an adding operation, moves the arcuate surface 324, on the extension 325, beyond the stud 310, and moves an engaging notch 348, in said extension, in alignment with said stud 310. Immediately after the notch 348 has been aligned with the stud 310, means (not shown) rocks the link 311 about its pivot to move the stud into the notch 348.

54. The timing of the mechanisms described above is such that the cams 254 and 255 (Fig. 6) have shifted the No. 1 totalizer wheels out of cooperative alinement with the transfer segments and into cooperative alinement with the amount actuators, and the differential mechanism for the first transaction bank has operated the drum cam 230 to align the selected set of wheels on the No. 1 totalizer line with said amount actuators prior to functioning of the totalizer line selecting mechanism. After the amount actuators have been positioned under influence of the depressed amount keys, and after the No. 1 totalizer line has been shifted laterally to align the selected set of wheels thereon with said actuators, the spider 326 (Fig. 5) is returned clockwise to shift the link 311 rearwardly to rock the lever 312 counterclockwise, which movement, by means of the link 314, rocks the lever 315 and the shaft 243 also in a counter-clockwise direction. Counter-clockwise movement of the lever 315 causes the roller 316, in cooperation with the camming slot 317, to shift the shaft 243 and the totalizer framework, including said shaft, the end plates 242 and 258, and the No. 1 totalizer line (Figs. 1 and 4), downwardly to engage the selected set of wheels with the amount actuators 104. The

totalizer framework is guided in its engaging and disengaging movements by the rollers 319 in cooperation with the radial slots 320, and by the slotted ends of the frames 242 and 258 in cooperation with the blocks 2441.

55. After the selected set of totalizer wheels has been engaged with the amount actuators, return movement of said actuators rotates said wheels in an additive direction to add therein the amount set up on the amount keys.

56. After the amount has been added in the selected set of totalizer wheels, the cams 338 and 339 (Fig. 5) return the spider 326 a slight distance counter-clockwise to partially disengage the totalizer wheels from the amount actuators.

57. During this partial disengagement, the cams 254 and 255 (Fig. 6) function to shift the selected set of totalizer wheels into cooperative alinement with the transfer segments, after which the spider 326 is returned clockwise to engage said selected totalizer wheels with said transfer segments. The transfer mechanism then functions in the manner explained earlier herein to effect the tens transfer.

58. At the end of machine operations, the engaging spider 326 remains in the position shown in Fig. 5; consequently, the No. 1 totalizer line remains in engaged position at the end of machine operation.

59. At the beginning of the succeeding operation and prior to initial movement of the actuators, the spider 326 returns the stud 310, the link 311, and associated parts forwardly to impart disengaging movement to the No. 1 totalizer line, and, when the stud 322 arrives opposite the right angle branch of the slot 323, the spring 321 immediately disengages the stud 310 from the notch 348 and engages said stud 322 with said right angle branch, as shown in Fig. 5. The notch 348 remains in alinement with the stud 310 until the totalizer line selecting mechanism again functions, so that said stud 310 may again be engaged with the notch 348 in case the No. 1 totalizer line is again selected for engaging and disengaging movement.

45

Operation

60. The novel tens transfer mechanism operates as follows:

61. The transaction keys 55 control the selection of a totalizer line by well-known means described in the parent application and in the patents referred to herein. After a line has been selected, a totalizer on the line is selected by the depressed control key 55, which, through the differential mechanism controlled thereby, rotates segment 223 and drum cam 230 to shift the desired totalizer into alinement with the amount actuators 104. Thereafter, the engaging mechanism shown in Fig. 5 engages the selected totalizer with the actuators 104, so that amounts set on the key-board can be entered in the totalizer.

62. When a totalizer wheel passes from 9 to 0, the long tooth 183 thereon trips yoke 181 to release arm 176, which at this time is arrested by stud 186, which stud at this time is in the dot-and-dash position (Fig. 2). After the amount has been entered into the totalizer, the totalizer is partially disengaged from the racks 104 by cams 338-339 (Fig. 5) and the mechanism operated thereby. Thereafter, the totalizer line is shifted by cams 254-255 (Fig. 6) to align the totalizer, into which the amounts were entered by the amount differential, with the transfer segments 170. After the totalizer wheels are engaged with the segments 170, the studs 186 are withdrawn to

75

their original position by cams 194—195 (Fig. 2) to release the tripped arms 176, which in turn releases the associated transfer segments 170 to enter the tens carries in the proper totalizer elements. Thereafter, the machine comes to rest.

Near the beginning of the next machine operation, the cams 338—339 disengage the totalizer from the actuators, and the cams 194—195 thereafter restore the tripped transfer segments 170 by moving the members 187 and the studs 186 clockwise slightly beyond the dot-and-dash position shown in Fig. 2. This movement of the studs 186 past such position rocks the members 176 counter-clockwise until the trip members 181 again latch the members 176 in the positions shown. During such counter-clockwise movement of the members 176, the studs 175 thereon move the transfer segments 170 back to their normal positions.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

What is claimed is:

1. In a machine of the class described having a totalizer line with a plurality of interspersed denominational sets of totalizer wheels thereon, the combination of a single set of actuators common to all of the totalizer wheels; means to position the actuators; means, including a single set of transfer segments located interspersed adjacent the single set of actuators, for transferring tens digits from lower to higher denominations; means actuated by the lower order totalizer wheels when moving from nine to zero to trip the transfer segments of the next higher orders; shifting means to shift the totalizer wheels laterally to align the selected set of said wheels, comprising one totalizer of said interspersed totalizers, with the actuators; means to engage the selected set of totalizer wheels with the actuators for actuation thereby and to disengage said set of totalizer wheels from said actuators; means to move one element of said shifting means to impart an auxiliary lateral shifting movement to the selected set of totalizer wheels, after the selected set of said wheels has been actuated, to align said selected set of wheels with the transfer segments; and means to operate the tripped transfer segments to effect a transfer of tens digits from lower to higher denominations.

2. In a machine of the character described having a laterally shiftable totalizer line with a plurality of denominational sets of interspersed totalizer wheels thereon, the combination of a single set of denominational actuators common to all of the totalizers; means to position the actuators; tens transfer means, including transfer segments interspersed adjacent the actuators; key-controlled means to shift the totalizer line to align a selected set of totalizer wheels with the actuators; means to engage the selected sets of totalizer wheels with the actuators for actuation thereby and to disengage said totalizer wheels from said actuators; means to trip the transfer segments of the next higher orders when the selected set of totalizer wheels of the next lower orders move from nine to zero while being actuated; automatic means effective, after the selected set of totalizer wheels has been actuated, to shift one element of said key-controlled means

from the position to which said one element was shifted into another position to shift said wheels into alignment with the interspersed transfer segments; and means effective after the selected set of totalizer wheels has been shifted into alignment with the transfer segments, to actuate said segments to cause tens digits to be transferred from lower to higher denominations.

3. In a machine of the character described, the combination of a shiftable framework; a totalizer line supported in the framework, said totalizer line having thereon a plurality of sets of denominational totalizer elements; actuators for the totalizer elements; means to position the actuators; means, including transfer members located adjacent the actuators, for transferring tens digits from lower to higher denominations; means actuated by the lower order totalizer elements when moving from nine to zero to trip the transfer members of the next higher orders; a cam operatively connected to the shiftable framework and mounted for rotary and/or lateral shifting movement; means to rotate the cam different extents to shift the framework in accordance therewith to select the various sets of totalizer elements for actuation by the actuators; means effective, after the elements of the selected set have been actuated, to shift the cam and the framework laterally to move said elements into cooperative relationship with the transfer members; and means to operate the transfer members to transfer tens digits from lower to higher denominations.

4. In a machine of the character described, the combination of a shiftable framework; a totalizer line supported in the shiftable framework, said totalizer line having thereon a plurality of sets of denominational totalizer elements; actuators for the totalizer elements; means to position the actuators; means, including transfer members located adjacent the actuators, for transferring tens digits from lower to higher denominations; means actuated by the lower order totalizer elements when moving from nine to zero to trip the transfer members of the next higher orders; a cam operatively connected to the shiftable framework, said cam adapted for rotary and/or horizontal shifting movement; means to impart horizontal shifting movement to the cam, said means effective to secure the cam against such movement when said cam is receiving rotary movement; control keys; means governed by the control keys to rotate the cam different extents to shift the framework in accordance therewith to select the various sets of totalizer elements for actuation by the actuators; and means effective, after the selected totalizer elements have been actuated, to effectuate the imparting means to cause said totalizer elements to be moved into cooperative relationship with the transfer members, whereupon the tripped transfer members function to effect the transfer of tens digits from lower to higher denominations.

5. In a machine of the class described, the combination of a horizontally shiftable totalizer line; a plurality of denominational sets of totalizer elements on the line; actuators for the totalizer elements; means located adjacent the actuators to transfer tens digits from lower to higher denominations; a cam adapted for rotary and/or horizontal shifting movement; means to impart horizontal shifting movement to the cam, said means effective to hold said cam against such movement when said cam is receiving rotary

movement; means, comprising a slide mounted on the imparting means, for operatively connecting the cam to the horizontally shiftable totalizer line; means to rotate the cam different extents to cause the slide to shift the totalizer line to select the different sets of totalizer elements for actuation by the actuators; and means effective, after the selected set of totalizer elements has been actuated, to effectuate the imparting means

5 to cause the totalizer line to be given an auxiliary horizontal shifting movement to move the selected set of totalizer elements into alignment with the transferring means, whereupon operation of said transferring means causes tens digits to be transferred from lower to higher denominations.
